CLINTON L. WOLFE AND JOSEPH A. FAUROT, OF NEW YORK, N. Y.

FOOT-ACTUATED SWITCH.

Application filed May 19, 1924. Serial No. 714,474.

This invention relates to circuit closing devices and particularly to a foot actuated circuit closing arrangement which finds particular utility in connection with the automatic door locking device shown and described in our copending application, Serial No. 652,434, filed July 18, 1923.

The invention is designed particularly for use in tellers' cages and cashiers' booths in banks and other institutions. The construction of the invention offers the possibility of the same being used as a foot rest by the teller or cashier, the invention when thus used being inoperative as a signal actuating device. However, the construction is such that the cashier or teller may, without any appreciable or noticeable movement or action, manipulate the device to close a circuit, causing an alarm or signal.

The invention furthermore contemplates the provision of means whereby the circuit closed by this device may be held closed until released whereby a signal or alarm may be continuously displayed or sounded until relief arrives or the device is reset.

The novel combination, construction and arrangement of parts constituting our improved invention will be more apparent as this description proceeds, especially when considered in connection with the accompanying drawings wherein:

Figure 1 is a front elevation of a circuit closing device constructed in accordance with our invention;

Fig. 2 is a top plan view; and

Fig. 3 is a vertical longitudinal sectional view taken substantially on the plane indicated by the line 3-3 in Figure 1.

As stated hereinbefore, this invention finds particular utility in connection with the structure shown in our aforementioned copending application, still, as this description proceeds, it will be readily apparent that its use is not limited in this connection but that it may be used with equal facility in many other ways. Furthermore, while the foot actuated circuit closing device described in our said copending application is employed to complete the circuit through the relay circuit breaker, this present invention may obviously be arranged directly in the signal circuit and upon actuation complete the circuit to the signal or alarm.

In the drawings it will be noted that the reference character 10 indicates the floor or base to which the device is attached, the base

plate 11 of each of the supporting standards being secured to the floor or base 10 in any suitable manner.

Extending upwardly from the base plate 11 is a hollow housing 12, which housing terminates in a cylindrical enlargement 13 open at one side and adapted to be closed by a screw cap 14. As will be apparent, two or more housings 12 are preferably employed and inasmuch as the structures are practically identical only one of the standards will be described in detail.

The reference character 15 indicates a tubular bar constituting a foot rest and constituting further the means by which the switch is actuated. This bar is mounted in brackets 16, one of which brackets is pivotally mounted as at 17 in each of the standards. These brackets are preferably substantially L-shaped, the depending leg 18 thereof being arranged adjacent to and longitudinally of the associated standard. Arranged within the hollow enlargement 13 of the casing is a pair of spring contacts 19 and 20, the contact 20 being engaged by a shoe 21 carried by a rod 22 fixed to the leg 18 of the bracket. The contacts 19 and 20 are shown of the push button type but obviously any suitable type of circuit closing elements may be employed in their stead. The contact 20 is engaged by the shoe 21 and upon proper manipulation of the foot bar 15 is pressed toward the contact 19 for closing the circuit. Wires 23 are shown, which wires will lead to the relay circuit breaker or to the signal if this device is placed directly in the signal circuit.

Each of the standards will preferably, although not necessarily be provided with the cylindrical enlargement 13 in which a pair of circuit closers will be positioned and if such be the case the wires from one pair of circuit closers to the other may be conducted through a wire encasing tube 24. Therefore, it will be necessary to make but one opening 25 through the base or floor 10.

Extending between the supporting standards and parallel with the foot bar 15 is a kick plate or abutment 26 vertically arranged and in position to be engaged by the toe of the operator. The bar 15 is ordinarily employed as a foot rest, the operator placing his feet on top thereof. When it is desired to operate the device the toe is placed under the bar 15 and the same is moved upwardly. Without this kick plate or abutment it would

be possible to inadvertently actuate the device by forcing the foot too far under the bar whereby the bar would be engaged by the top of the foot and be raised sufficient to close the switches. However, owing to the provision of this kick plate or abutment, the insertion of the operator's foot inadvertently under the device is prevented and accidental closing of the alarm circuit prevented.

10 Contemplating the desirability and necessity of providing means for maintaining the circuit closed after it has once been completed, we provide a latch 27, the depending end 28 of which is arranged within a guide housing 29 within which there is also arranged a spring 30. The latch 27 is slidably mounted and is constantly urged in an upward direction by the spring 30. A knob 31 extending outwardly from the latch 27 through a slot 32 limits the movement of the latch, the knob further providing means for releasing the latch when desired. The active face of the latch is beveled as at 33 and is adapted to be forced under the depending leg 18 of the bracket 16 after the bar 15 has been raised. Consequently the bar will be held in its raised position while the switches will be held closed by reason thereof. The bevel 33 of the latch is such that the latch may be forced downwardly by a pressure on top of the foot bar 15 or the bar 15 may be released by depressing the latch 27 through the medium of the knob 31 in which event the bar 15 will drop to inoperative position by gravity.

15 The provision of means whereby the circuit controlled by this device may be held closed until released offers the possibility of providing arrangements with the police authorities or other protective agency whereby false alarms may be rectified. It would be possible to arrange that should the alarm be sounded for longer than a certain specified period, the police should respond. In the 20 event, however, that the signal was not sounded continuously for this period and over, the alarm would be considered a false

one and response from the police would be unnecessary. Thus, if the device were inadvertently operated the mistake would be immediately detected at the institution at which this device is installed and the bar could be released, thus breaking the circuit and causing the signal to cease functioning. However, in the event the device was operated 25 for cause and the signal or alarm set in operation and the teller or cashier then overpowered, the signal would continue to function until relief was obtained.

30 The details of this invention have been described herein with some particularity but it will be readily apparent to those skilled in this art that the device may be associated with numerous types of signal arrangements and also that the details of construction herein shown may be varied without departing from the spirit and scope of the invention.

35 Having thus described our invention, what we claim is:

1. A circuit closing device comprising a 40 bar constituting a foot rest, a pair of supporting standards, brackets pivotally mounted on said standards and swingingly supporting said bar, a circuit closing device actuated by one of said brackets when said bar is raised, one of said brackets being provided with a depending leg, a spring pressed latch mounted on one of said standards adjacent said leg and adapted to be forced under said leg when said bar is raised whereby said bar may be held in circuit closing position.

45 2. A circuit closing device in accordance with claim 1 in which the surface of said latch which is forced under said depending leg is bevelled at such an angle that it will cause said latch to be forced from under said depending member when said bar is forced down.

50 The foregoing specification signed at Woodhaven, New York city, N. Y., this 15th day of May, 1924.

CLINTON L. WOLFE.
JOSEPH A. FAUROT.
